UNITED STATES PATENT OFFICE.

AARON A. BELLEAU, OF BROOKLYN, NEW YORK.

AUTOMATIC FAUCET.

SPECIFICATION forming part of Letters Patent No. 487,384, dated December 6, 1892.

Application filed July 25, 1892. Serial No. 441,080. (Model.)

To all whom it may concern:

Be it known that I, AARON A. BELLEAU, of Brooklyn, Kings county, New York, have invented an Improved Automatic Faucet, of 5 which the following is a specification.

This invention relates to a faucet for filling smaller barrels or other receptacles from a main tank and which is so constructed that when the barrel is full the faucet will be 10 closed and its discharge-nozzle will be raised out of the barrel.

The invention consists in the various features of improvement more fully pointed out in the claims.

15 In the accompanying drawings, Figure 1 is an elevation, partly in section, of my improved faucet, showing it lowered; Fig. 2, an elevation of the same, showing it raised; Fig. 3, a top view of the operating mechanism; 20 Fig. 4, a section on line $x-x$, Fig. 3; Fig. 5, a section on line $y-y$, Fig. 3; Fig. 6, a rear view of Fig. 3; Fig. 7, a section similar to Fig. 4, showing the parts in a different position.

The letter a represents the inlet-pipe, connected with a suitable main delivery-tank. 25 This pipe is provided with a cock a' , through which the liquid flows into a horizontal slotted tubular bearing a^2 . Upon this bearing there is free to revolve a slotted sleeve b' , connected at one side with the discharge-pipe b and at the other side with a lever b^3 , which is weighted, as at b^3 . The discharge-pipe b is 30 provided with a nozzle b^4 , that enters the barrel or other receptacle A to be filled. The nozzle b^4 is provided with a longitudinal partition b^5 to form two chambers. One of these 35 chambers constitutes the nozzle proper through which the liquid is discharged. Within the other chamber is placed a float c , connected by bell-crank c' and suitable rod c^2 to a catch c^3 , pivoted to the tube b . This catch is adapted to engage a hook d' of a fixed 40 bracket d , that is also provided with a bearing d^2 for the tube.

45 As so far described the apparatus operates as follows: The liquid flowing through the tube a , cock a' , and hollow bearing a^2 enters pipe b and through nozzle b^4 is discharged into the barrel A . During this operation the 50 tube b is in its horizontal position, resting upon bearing d^2 and held down by the engagement of the hooks c^3 d' , Fig. 1. As soon as

the liquid has filled the barrel A it will raise the float to oscillate hook c^3 , which will thus become disengaged from the hook d' and permit the weight b^3 to swing the tube b upward and out of the barrel, Fig. 2.

In order to automatically open and close the cock a' at the proper time, I have devised the following mechanism: Upon the hollow 60 spindle a^2 there turns freely a double segment e , having teeth e' at one end and a bevel-gear e^2 at the other end. The bevel-gear is engaged by a segment f , having bevel-teeth and fast upon the spindle a^3 of cock a' . The 65 teeth e' are engaged by a toothed segment g , pivoted to the weighted arm b^2 . When the pipe b is lowered, the segment g is raised until the pipe b has arrived at nearly its lowermost position, when a rearwardly-extending 70 arm g' of segment g will strike against a fixed stop d^3 on the bracket d . This will cause the segment g to revolve on its pivot and to thus cause a revolution of segment e . This segment, intergearing with segment f on 75 the cock-spindle, will thus open the cock. It will be seen that the above-described mechanism will open the cock suddenly as the nozzle b^4 is dipped into the barrel A in contradistinction of causing an objectionable gradual opening of the cock during the entire 80 downward motion of pipe b . When the barrel A has been filled and the pipe b is raised out of the same by the disengagement of the hooks d' c^3 in the manner described, it will 85 take the segment e with it. This is accomplished by means of a shoulder e^3 on the segment e , that engages a corner b^4 on the sleeve b' during the upward motion of pipe b , Fig. 4, but not during the downward motion, Fig. 90 7. The segment e , being thus revolved backward, will revolve segment f to close the cock a' . At the same time the segment e will revolve segment g ; but this will merely cause a revolution of the segment g upon its pivot 95 without producing any effect upon the cock.

In order to permit the cock to be opened and closed by hand, if desired, the shoulder e^3 may be provided with a handle e^4 . By manipulating this handle the barrel A may be 100 filled when it is desired not to have the upward and downward motion of pipe b .

The operation of the apparatus will be readily understood. The pipe b being lowered by

hand, so that its nozzle enters the barrel, the cock a' will be opened and the liquid will flow into the barrel until the latter is filled. Then the float will be raised, the pipe will be 5 tilted, so that its nozzle is withdrawn from the barrel, and the cock will be closed.

What I claim is—

1. The combination of an inlet-pipe with a cock, a pivoted weighted outlet-pipe having 10 a nozzle and a catch, a hook engaging the catch for holding the pivoted pipe in its lowermost position, and with a float within the nozzle connected to the catch, substantially as specified.
- 15 2. The combination of an inlet-pipe with a cock, a pivoted outlet-pipe having a nozzle and a catch, a float, a toothed segment f upon the cock-spindle, and a toothed segment e , having a shoulder e^3 and adapted to operate 20 segment f , substantially as specified.
- 20 3. The combination of an inlet-pipe with a cock, a pivoted outlet-pipe having a nozzle

and a catch, a float, a loosely-turning toothed segment e , having teeth $e' e^2$, and with a fixed segment f upon the cock-spindle, and a pivoted segment g , adapted to engage segment e , substantially as specified. 25

4. The combination of an inlet-pipe with a cock, a pivoted outlet-pipe having a nozzle and a catch, a float, intergeared segments e 30 $f g$, and with a stop d^3 and catch d' , substantially as specified.

5. The combination of an inlet-pipe with a cock, an outlet-pipe, a double-toothed segment e , free to turn in one direction, a toothed segment f , fast on the cock-spindle and engaging segment e , and with a pivoted segment g , also engaging segment e , substantially as specified. 35
